CONVERTIBLE BOX

Ella M. Lapham, 3927 S. Las Flores Canyon Read,
Malibu, Calif.

Filed July 27, 1961, Ser. No. 127,361
2 Claims. (Cl. 206—45)

This invention relates generally to convertible box structures and more particularly to a novel box structure serving as a container for various articles and convertible into a multi-compartmented structure defining different shelf levels for conveniently storing the articles.

There are many articles to which ready access is desirable, particularly as used in the home such as different spice boxes, cosmetic bottles, etc. Generally, a kitchen cabinet or conventional type shelving is more than adequate in height and area to accommodate articles of this type. However, when a large number of such articles are stored, some become pushed behind others and thus are not accessible. The problem may be overcome by constructing intermediate shelves of half-heights so that bottles or small containers ordinarily concealed behind other bottles or containers may be placed on the half-height shelves to be readily accessible. Such a solution, however, requires the obtaining of shelf material and actual construction of the auxiliary shelves.

With the foregoing in mind, it is a primary object of this invention provide a novel convertible box which serves the dual function of storing various articles for shipping and also, by a simple converting process, provides multi-leveled shelves for supporting the articles on conventional shelves in readily accessible positions.

Briefly, this object is achieved by providing a convertible box including a cover having four sidewalls and a container having four sidewalls dimensioned to be nested within the sidewalls of the cover when the cover is positioned over the container to ship or otherwise store various articles in the same manner as in a conventional box. In accordance with an important feature of the invention, adjacent sidewalls of the cover are provided with slots running normally to the top surface of the cover. The floor of the container in turn is also provided with a pair of slots defining a general L-shape. The floor slots of the container are dimensioned to receive the sidewall portions between the cover slots after the cover has been removed and the container portion turned over or inverted. The resulting assembly defines a multi-compartmented container which, when stood on one of the sidewalls opposite the adjacent sidewalls of the cover, define multi-leveled shelves for supporting the various articles.

A better understanding of the invention will be had by referring to a preferred embodiment thereof as illustrated in the accompanying drawings, in which:

FIGURE 1 is an exploded perspective view illustrating the convertible box of this invention;

FIGURE 2 is a rear view of the cover and container portions of the box in assembled relationship;

FIGURE 3 is a front elevational view of the structure illustrated in FIGURE 2; and

FIGURE 4 is another front elevational view illustrating one manner in which the box may be employed for supporting various articles.

Referring first to FIGURE 1, the convertible box comprises a cover 10 and a container 11. The cover 10 includes four sidewalls as shown, two adjacent sidewalls 12 and 13 being provided with cover slots 14 and 15 centrally cut in the sidewalls and extending normally from the top surface 16 of the cover. As shown, the slots terminate at the edges of the adjacent sidewalls.

The container 11 is shown in an inverted or upside down position, the floor 17 being provided with slots 18

2

and 19 extending inwardly from adjacent sidewalls 20 and 21 to intersect at the central area of the floor. The slots 18 and 19 define a general L-shape. The initial starting points for these slots at the adjacent sidewalls 20 and 21 of the container portion 11 are designated 20' and 21', respectively. The straight line distance between these initial starting points is shown by the dimension D. This distance is equal to the distance between the cover slots 14 and 15 also designated by the letter D. With this arrangement, the sidewall portions between the corner 22 and the slots 14 and 15 define tabs 23 and 24 respectively receivable within the slots 18 and 19 in the floor 17 of the container when the cover is moved towards the bottom or floor of the container.

When the cover 10 has its tab portions inserted within the slots 18 and 19 as described, the assembled structure will appear as shown in FIGURE 2.

If now the entire assembly is inverted or rotated about a horizontal axis so as to view the front, the structure will appear as shown in FIGURE 3 wherein multiple compartments are defined.

Referring now to FIGURE 4, the cover and container portions 10 and 11 are in the same assembled relationship as illustrated in FIGURE 3 and are shown disposed on a shelf 25. A sidewall opposite to one of the adjacent sidewalls of the cover serves as a stand for the structure. The right hand sidewall of the container 11 as viewed in FIGURE 4 in turn rests flush against the vertical side 26 for the shelf 25. The shelf 25 and vertical side or jamb 26 may constitute a portion of a conventional kitchen cabinet or medicine chest. With the box structure positioned as shown, various articles such as spice containers or cosmetic bottles 27 may be stored. Taller bottles or containers such as indicated at 28 and 29 may be positioned in the vertically larger compartmented areas so that several different sized items may be accommodated.

As indicated by the dashed horizontal lines in FIGURE 4, the box structure in the condition illustrated defines essentially four shelves or levels upon which articles may be placed. These levels are indicated by the letters a, b, c, and d.

In the particular embodiment chosen for illustrative purposes, the cover and container structures of the box are substantially square constituting a special case of a rectangle. It will be understood, however, that the structure may take the form of elongated rectangles or other equivalent shaped boxes. Further, it will be appreciated that the slots need not be cut at the mid-portions of the sidewalls for the cover or initiate at the mid-portions of the floor sides for the container but may be varied as desired to define shelves of different levels and area. It should also be understood, of course, that the slots in the container could be formed in the top surface of the cover and the slots in the sidewalls of the cover formed in the sidewalls of the container so that the cover and container are effectively reversed. The terminology of "cover" and "container" as used herein and in the claims may thus be interchanged.

It will be apparent, accordingly, that various modifications and changes may be effected without departing from the scope and spirit of the invention. The convertible box is therefore not to be thought of as limited to the one embodiment set forth merely for illustrative purposes.

What is claimed is:

1. A convertible box comprising, in combination: a rectangular cover having four sidewalls; and a rectangular container having four sidewalls adapted to be nested with the sidewalls of said cover when said cover is positioned to close said container, cover slot means comprising two slots cut respectively in adjacent sidewalls of said cover so that said sidewall portions of said cover include a corner, the floor of said container including an L-shaped slot

means dimensioned to receive the sidewall portions of said cover between said two slots when said cover is removed and said container is turned over, whereby a plurality of separate compartments are defined by said cover and container.

2. A convertible box comprising, in combination: a rectangular cover having four sidewalls; and a rectangular container having four sidewalls adapted to be nested with the sidewalls of said cover when said cover is positioned to close said container, two adjacent sidewalls of said cover having central cover slots running in a normal direction from the top surface of said cover and terminating at the edges of said adjacent sidewalls, the floor of said container having two container slots running normally from central points on adjacent sidewalls of said con-

5 tainer to terminate at a common intersection point in the middle area of said floor, the distance between said cover slots being substantially equal to the distance between the starting points of said container slots, whereby said cover may be removed, said container turned over, and the side tabs defined between said cover slots and the common corner of said first mentioned adjacent sidewalls inserted within said container slots respectively to define a compound container structure defining four shelf levels when said cover is positioned to stand on a sidewall opposite one of said first mentioned adjacent sidewalls.
